NORMAN P. HARSHBERGER, OF PASADENA, CALIFORNIA

ROOFING MATERIAL

Application filed July 12, 1928. Serial No. 292,079.

This invention relates to improvements in roofing material and method of forming the same.

It is one of the objects of this invention to provide an improved roofing material which may be formed either in single units or in strips comprising a plurality of units, each of said units being so constructed as to permit them to be laid in interlocking relation with one another, the particular interlocking means differing from anything heretofore used in the art, and greatly expediting the laying of roofs.

It is a further object of this invention to provide an improved roofing material and method of forming the same which permits units or strips to be cut in the proper size and shape from a sheet of material in such a manner that there is practically no material wasted.

It is a further object of this invention to provide an improved roofing material in which this interlocking means is so formed that when the units are being laid on a sloping roof, the engagement of one unit with another takes place from above in a downwardly direction, the units being maintained in position by their own weight prior to being nailed down. Heretofore, in the type of interlocking means employed, the engagement of one unit with another was effected from below in an upwardly direction making it necessary to manually hold the units in place until secured by nails.

It is a more specific object of this invention to provide an improved roofing material in the form of shingles, each shingle comprising a body portion and a tab portion, the body portion being formed with a tongue preferably in the form on an inverted T, and the tab portion being formed with a recess for engaging the tongue of the shingle below, a portion of the tongue being of greater width than a portion of the recess to permit overlapping of the edges of the recess.

It is a further object of this invention to provide an improved roofing material and method of forming the same, which is simple and inexpensive to manufacture, and well adapted for the purpose described.

With the above and other objects in view, the invention consists of the improved roofing material and method of forming the same, and all its parts and combinations as set forth in the claims, and all equivalents thereof.

In the accompanying drawing, in which the same reference characters designate the same parts in all of the views:

Fig. 1 is a plan view of a blank, the lines showing the manner of cutting to produce a plurality of roofing strips;

Fig. 2 is a fragmentary plan view of a roof covered with the improved form of roofing material;

Fig. 3 is a view of a strip comprising two units or shingles; and

Fig. 4 is a view of a single unit.

Referring to the drawing, the numeral 5 designates a sheet of composition or other material such as is commonly employed in covering roofs. The sheet is cut on the lines 5' as indicated in Fig. 1, to form a plurality of strips as shown in Fig. 3. Each strip may comprise two shingles as illustrated, or it may comprise a greater number. If it is more convenient for a particular piece of work each shingle may be cut separately as in Fig. 4.

Each shingle as cut consists of a body portion 6, and a tab portion 7. The lower edge of the tab portion is formed with a recess 8, the material removed in forming said recess being the only waste in this improved method of forming the shingles. The lower edge of the body portion adjacent the tab, and midway between two tabs in the case of a strip consisting of a plurality of shingles, has a pair of cuts extending upwardly; then at right angles toward one another, and then upwardly to form an inverted T-shaped tongue 9, the lower portion of the tongue being of greater width than the recess to permit overlapping of said recess.

The body portion of either a separate shingle or a strip of shingles extends outwardly a greater distance on one side than on the other as at 10. The purpose of this is to provide sufficient material to form a full tongue 9. As no tongue is formed on the other side, the body material extends outwardly only a short distance as at 11.

In cutting the shingles from the blank shown in Fig. 1, the space between the tabs of one row of strips is utilized to form the tabs of another row of strips, so that in cutting longitudinally through the blank, on an irregular line the tabs of two rows of strips are formed simultaneously without waste of material.

The particular shape of the shingles is immaterial, as they may be cut to form any desired design. By forming the tabs with converging sides as shown, the finished roof has the appearance of being made up of a plurality of hexagonal shingles in staggered relation with one another.

In laying the shingles on a roof, a plurality of strips or separate shingles are placed adjacent one another to form a row, and their body portions are secured to the roof by 20 nails or other suitable means. In laying the next row, the shingles or strips are inserted from above so that the edges of the recesses 8 of the tabs fit underneath the lower portions of the T-shaped tongues as shown in 25 Fig. 2. The shingles will thus be held in place on a slanting roof by their own weight, until permanently secured by nails. It will be seen that the interlocking means provides a very positive engagement between the shingles and insures the proper positioning of the shingles with relation to one another so that the design will be uniformly carried out. It is to be further noted that this improved roofing material provides a covering of two 30 and three thicknesses in which no nails are exposed thereby eliminating the possibility of leakage.

From the foregoing description, it may be seen that the improved roofing material 40 makes it possible to quickly and inexpensively cover a roof so as to give the maximum protection and so as to provide a roof which is neat and attractive in appearance.

What I claim is:

45 1. A covering for roofs comprising a section of material having a portion formed with a recess and having another portion formed with a tongue, said tongue being formed by converging cuts in the same edge 50 portion extending inwardly therefrom, a portion of said tongue being of greater width than a portion of the recess, the said recess being engageable with the tongue of a like section of material, and the said tongue being engageable with the recess of another like section of material.

60 2. A covering for roofs comprising a section of material having an edge portion formed with a recess and having another portion formed with a tongue, said tongue being formed by converging cuts in the same edge portion extending inwardly therefrom, a portion of said tongue being of greater width than a portion of said recess, the said recess 65 being engageable with the tongue of a like

section of material and the said tongue being engageable with the recess of another like section of material positioned above to support said section against downward movement.

70 3. A covering for roofs comprising a section of material having an edge formed with a U-shaped recess, and having a portion formed with an inverted T-shaped tongue, the lower portion of said tongue being of greater width than the U-shaped recess, the 75 said recess being engageable with the tongue of a like section of material, and the said tongue being engageable with the recess of another like section of material, positioned above to support said section against downward movement.

75 4. A covering for roofs comprising a section of material having a body portion and having a tab portion extending therefrom, the lower edge of the tab portion being formed with a recess, and the lower edge of the body portion being formed with a tongue, said tongue being formed by converging cuts extending upwardly from said lower edge, the lower portion of said tongue being of greater width than a portion of said recess, and said recess being engageable with the tongue of a like section of material, and said tongue being engageable with the recess of another like section of material.

80 5. A covering for roofs comprising a section of material having a body portion and having a tab portion extending therefrom, the lower edge of the tab having a portion 85 cut out to form a recess, and the lower edge of the body having a pair of cuts extending inwardly, and then toward one another to form a tongue with side flaps, said recess being engageable with the tongue of a like section of material, and said tongue being engageable with the recess of another like section of material, the side flaps of the tongue overlapping the edges of the recess.

85 6. A covering for roofs comprising a section of material having a body portion and having a tab portion extending therefrom, the lower edge of the tab having a portion 90 cut out to form a U-shaped recess, and the lower edge of the body portion having a pair of cuts extending inwardly and then toward one another and then inwardly again to form an inverted T-shaped tongue, the lower portion of said inverted T-shaped tongue being of greater width than the U-shaped recess of the tab portion, the said tongue being engageable with the recess of a like section of material, and the said recess being engageable with the tongue of another like section of material.

95 7. A covering for roofs comprising a section of material having an edge cut out to form a recess and having another edge provided with a pair of cuts extending inwardly and then toward each other to form a tongue

with side flaps, said recess being engageable with the tongue of a like section of material, and said tongue being engageable with the recess of another like section of material, the 5 side flaps of the tongue overlapping the edges of the recess.

8. A covering for roofs comprising a section of material having a portion formed with a recess and having another portion 10 formed with a tongue, said tongue being formed by converging cuts in the same edge portion extending inwardly therefrom, the distance between the inner portions of said cuts being less than the width of said recess 15 and the distance between the outer portions of said cuts being greater than the width of said recess, the said recess being engageable with the tongue of a like section of material and the said tongue being engageable with 20 the recess of another like section of material.

9. A covering for roofs, comprising a section of material having a body portion and having a tab portion extending therefrom, the lower edge of the tab portion being 25 formed with a recess, and the lower edge of the body portion being formed with a tongue, the lower portion of said tongue being of greater width than a portion of said recess, and said recess being engageable with the 30 tongue of a like section of material, and said tongue being engageable with the recess of another like section of material.

10. A covering for roofs, comprising a section of material having an edge formed with 35 a recess and having a portion formed with a tongue, the lower portion of said tongue being of greater width than the recess, the said recess being engageable with the tongue of a like section of material, and the said tongue 40 being engageable with the recess of another like section of material positioned above to support said section against downward movement.

In testimony whereof, I affix my signature.
45 NORMAN J. HARSHBERGER.
